Primary Examiner — T. Chase Nelson*Assistant Examiner* — Ania Aman(74) *Attorney, Agent, or Firm* — Robert L. Stearns;
Dickinson Wright PLLC(57) **CLAIM**

We claim the ornamental design for a piston, as shown and described.

DESCRIPTION

FIG. 1 is a perspective view of the piston;
FIG. 2 is a top view of the piston;
FIG. 3 is a side view of the piston;
FIG. 4 is cross-sectional view of the piston taken along line 4-4 of FIG. 5;
FIG. 5 is a side view of the piston rotated 90 degrees from FIG. 3;
FIG. 6 is cross-sectional view of the piston taken along line 6-6 of FIG. 3;
FIG. 7 is a bottom view of the piston; and,
FIG. 8 is a bottom perspective view of the piston.

1 Claim, 5 Drawing Sheets---
